Primary Examiner — Elizabeth Albert(74) *Attorney, Agent, or Firm* — J. Curtis Edmondson;
Anitha Shankarnarayan; Law Offices of J. Curtis
Edmondson**CLAIM**

We claim the ornamental design for a dry erase board pivoted to a table, as shown and described.

DESCRIPTION

FIG. 1 is a perspective view of a dry erase board pivoted to a table showing my new design;

FIG. 2 is a front side view thereof;

FIG. 3 is a back-side view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of the dry erase board pivoted to a table.

FIG. 9 is a front side view thereof;

FIG. 10 is a back-side view thereof;

FIG. 11 is a left-side view thereof;

FIG. 12 is a right-side view thereof;

FIG. 13 is a top view thereof; and,

FIG. 14 is a bottom view thereof.
